UNITED STATES PATENT OFFICE.

JOHN R. ROGERS, OF BROOKLYN, NEW YORK.

DEVICE FOR TRANSMITTING POWER.

Application filed October 30, 1920. Serial No. 420,668.

The devices hereinafter described may be considered as improvements upon my application, Serial Number 402,032 filed Aug. 20, 1920 and Patent No. 1,256,596 granted 5 to me on the 19 day of February, 1918.

The object of the device is to control the speed of a driven shaft by the resistance encountered by said shaft, and establish such a relation between the driving and the 10 driven shafts that as the resistance increases on the driven shaft, at a certain point, it will revolve at a lower speed, but with greater torque, while the driving shaft revolves at constant speed with any given 15 power.

In the following I have described, in connection with the accompanying drawings, one form of device illustrating the application of my invention to means for controlling the speed of an automobile.

Referring to the drawings, Figure 1 is a perspective view of the device as applied to an automobile, looking from the front of the machine, the cover being removed and parts 25 being broken away.

Figure 2 is a view, similar to Fig. 1, showing in dotted lines a form of construction as actually made and used, parts being broken away.

Figure 3 is a view, on a smaller scale than Fig. 1, of the parts shown in Figure 1, removed from the casing and omitting certain lines for the sake of clearness, parts being broken away.

Figure 4 is a view, on the scale of Fig. 3, of the rear portion of the device shown on Figure 1, the rear cover being removed.

Figure 5 is a vertical section through Figure 1 on the lines 5 . . . 5, the shafts being 40 shown in full lines.

Similar letters of reference indicate similar parts throughout the several views.

Referring to Figures 1 and 2, A is a drum or casing, the front wall or cover of which 45 has been removed.

B is a plate loosely mounted on the driving shaft S in any suitable manner, such as is hereinafter described. Fast to the plate B are two blocks H..H. Between the 50 blocks H..H are two rods G..G, mounted at either end in the blocks H..H. Surrounding the rods G..G are two powerful springs I..I.

On the driving shaft S and secured to it 55 is an eccentric C. This eccentric revolves inside of a casing D. Pivotaly mounted on

the casing D are two arms E..E, pivotally connected at their outer ends to sleeves F..F adapted to slide on the rods G..G. Springs I..I bear at one end against sleeves F and at 60 the other against stops R on rods G.

As the eccentric C is revolved by driving shaft S, through the action of casing D, arms E and sleeves F, the springs I, under certain conditions hereinafter described, are 65 alternately compressed and allowed to expand again. The action of this eccentric C through the springs tends to cause the plate B to revolve clockwise.

Securely fastened to the back of plate B 70 by suitable bolts is a spur-gear L. The spur-gear L is loosely mounted upon an eccentric C' secured to driving shaft S. During the revolution of the eccentric C', the spur-gear L is in mesh constantly with an 75 internal gear K.

The internal gear K is securely fastened to the drum or casing A and is mounted concentric with shafts S and S', the drum A being splined or otherwise fastened, to 80 the driven shaft S'.

The eccentrics C and C' have upon their surfaces suitable ball-bearings to avoid friction.

In Figure 4, K is the internal gear and 85 L the spur-gear mounted eccentrically to the driving shaft S.

Figure 5 shows the driving shaft S, the driven shaft S', the plate B having secured to it the spur-gear L, and the drum or casing A, carrying the internal gear K, said drum or casing being secured to the driven shaft S', as above described.

In the operation of the device, the driving shaft S is assumed to be revolved by the 95 engine clockwise. This carries around the eccentric C which tends to compress the springs I and to revolve the whole mechanism clockwise. So long as the springs I do not compress, the teeth in the gear L 100 will remain in contact with the corresponding teeth in the internal gear K, there being no gear action between them. At this time the driving shaft S is driving the driven shaft S' at the same speed with 105 which it itself revolves. At this time the whole mechanism is revolving integrally, or as a unit at the speed of the engine.

When, however, the resistance on the 110 driven shaft S' becomes so great as to cause the springs I to compress and expand, a different action takes place. The eccentric

C' in its revolution now compels the spur-gear L to move around the shaft S eccentrically, thereby driving the internal gear K forward by an amount equal to the difference between the number of teeth in the gear L and the number of teeth in gear K, thereby obtaining an increased amount of torque in proportion to the difference in the number of teeth between the spur-gear L and the internal gear K.

When the resistance on the driven shaft S' becomes so great that the plate B stands still with reference to the gear K, the gear K is revolved forward one revolution for the number of its teeth divided by the difference between the teeth of the gears L and K. In the machine constructed, the gear L has 44 teeth and the gear K has 51 teeth, making a difference of 7 teeth. Eccentric C', therefore, makes seven and two-sevenths of a revolution for one revolution of the gear K under the circumstances above mentioned.

Experience has shown that between the integral revolution of the whole mechanism as first described, and the point at which the plate B stands still with reference to the gear K, there are an infinite number of intermediate speeds, that is to say, the springs I are tending to revolve the whole mechanism as an integer, while their compression and expansion allows the eccentric C' to operate through the gear L with an increased torque on the gear K which is fast on the driven shaft S'. The speed of the driven shaft S' is the result of the sum of the forces exerted through the springs, and by the eccentric and is governed exactly by the resistance on the driven shaft S'.

The applicant is well aware that the action of an eccentric, such as C' through a gear, such as L, upon an internal gear, such as K, is not new, but in every case known to the applicant the gear L is attached in some way to a fixed point outside of the mechanism. This is usually done by an arm or lever attached to the gear L, and having a slot in it, in which a pin works, which pin is attached rigidly to something outside of the mechanism.

When such pin and arm is used, the eccentric C' is always working and the driven gear K is always revolved at a lower speed than the eccentric, such speed being directly proportional to the difference between the number of teeth in the gear L and the gear K, as above described.

The difference between the action last mentioned and the action of applicant's device, is primarily due to the fact that the reaction of a gear, such as gear L, upon a gear, such as gear K, in the old device, is partly against a fixed pin outside of the mechanism in connection with a slotted lever fast to the gear L, while in applicant's de-

vice, the reaction of the gear L when it is acting on gear K, is against the springs I.I and through linked arms E.E., against the driving shaft S.

The reaction in applicant's device allows the whole device to revolve integrally when the resistance on driven shaft S' is less than the resistance of springs I.I, but when the resistance on driven shaft S' is greater than the resistance of the springs I.I., then the springs compress and expand and both actions, that is, action through the eccentrics and through the springs I.I. takes place at the same time.

In the old device the action of the gear, such as gear L, upon the gear, such as gear K, is constantly reacting against the fixed pin and there is always a constant difference between the speed of the gears and hence between the driving and driven shafts.

The applicant believes that he is the first to eliminate the fixed pin and lever or its equivalent and allow the reaction of the gear L to come against a yielding connection attached to the driving shaft S and tending to revolve with it.

By the use of this mechanism the power of the eccentrics C and C' can be applied through the springs alone, or through the gears reacting against the springs, or through both gears and eccentrics at the same time.

Experience has shown that even when the resistance of the driven shaft S' is so great that the plate B goes backward slowly, the same action above described continues.

Experience has also shown that the tension of the springs I should preferably be about four-fifths of the total torque exerted on the driving shaft S. In the car used for experimenting, the torque developed by the engine is about 1500 inch-pounds. The springs were, therefore, designed to give a resistance of about 1200 inch-pounds.

There are many advantages which will be obvious in the use of this mechanism. The gears are constantly in mesh and do not have to be changed in order to get an increase in torque.

The ordinary clutch is not necessary and in some cases, at least, an ordinary dog clutch is all that is required. Under any ordinary circumstances with full throttle, the engine cannot be stalled. In starting or in going up a steep incline, the springs work, and the speed is proportionate to the resistance applied to the rear wheels.

Any suitable device may be used for connecting the gears K and L so that the entire torque of the engine may be used on a level road. This device can be worked by either hand or foot.

While I have shown this mechanism as applied to an automobile, I do not limit myself to such use, as I believe that in many

cases where power is to be transmitted and the resistance varies on the driven shaft, this mechanism will be found of use.

While I have shown in the drawings and 5 described in the specification, as well as claimed in some of the claims, springs as the yielding medium, I do not restrict myself to springs only, as it is obvious that other equivalent yielding means, such as a 10 piston and cylinder for instance, could be used. I however prefer to use springs.

Where the word "differential" is used in the claims it is used in the broad sense and not in the narrow sense as colloquially applied to the gear on the rear axle of an 15 automobile.

Having described my invention and what I claim is:

1. In a mechanism for transmitting power, 20 a driving shaft, a driven shaft, an eccentric on said driving shaft, a gyratory gear freely mounted on said eccentric, a gear secured to the driven shaft and meshing with said gyratory gear and yieldable means 25 operatively connecting said gyratory gear with said driving shaft.

2. In a mechanism for transmitting power, a driving shaft, a driven shaft, an eccentric on said driving shaft, a gyratory gear freely 30 mounted on said eccentric, a gear secured to the driven shaft and meshing with said gyratory gear and a spring carried by the gyratory gear and means cooperating therewith connected with the driving shaft.

3. In a mechanism for transmitting power, 35 a driving shaft, a driven shaft, an eccentric on said driving shaft, a gyratory gear freely mounted on said eccentric, an internal gear secured to the driven shaft and meshing with 40 said gyratory gear, a second eccentric mounted on the driving shaft and yieldable means operatively connecting said gyratory gear with said driving shaft through said second eccentric whereby the gyratory gear is 45 adapted to react entirely against the driving shaft and yieldingly restrained movement is independently permitted between the gyratory gear and the driven shaft.

4. In a mechanism for transmitting power, 50 a driving shaft, a driven shaft, an eccentric on said driving shaft, a gyratory gear freely mounted on said eccentric, an internal gear secured to the driven shaft and meshing with said gyratory gear, a second eccentric 55 mounted on the driving shaft and spring controlled means operatively connecting said gyratory gear with said driving shaft through said second eccentric, whereby the gyratory gear is adapted to react entirely 60 against the driving shaft and yieldingly re-

strained independent movement is permitted between the gyratory gear and the driven shaft.

5. In a mechanism for transmitting power, 65 a driving shaft, a driven shaft, an internal driven gear fast on the driven shaft, an eccentric fast on the driving shaft, a driving gear revolvably mounted on said eccentric meshing with the internal driven gear, a second eccentric fast on the driving 70 shaft and a yielding connection between said second eccentric and said driving gear whereby yieldingly restrained independent movement is permitted between the driving gear and the driven shaft. 75

6. In a mechanism for transmitting power, 80 a driving shaft, a driven shaft, a gear fast on the driven shaft, an eccentric fast on the driving shaft, a driving gear loosely mounted on said eccentric meshing with the gear on the driven shaft, a plate fast to said driving gear, a second eccentric fast on the driving shaft and a yielding connection between said second eccentric and said plate whereby yieldingly restrained independent movement 85 is permitted between the driving gear and the driven shaft.

7. In a mechanism for transmitting power, 90 a driving shaft, a driven shaft, a gear fast on the driven shaft, an eccentric fast on the driving shaft, a driving gear loosely mounted on said eccentric and meshing with the gear on the driven shaft, a plate fast to said driving gear, a second eccentric fast on the driving shaft, springs mounted on said plate 95 and means controlled by said second eccentric through said springs whereby yieldingly restrained independent movement is permitted between the driving gear and the driven shaft. 100

8. In a mechanism for transmitting power, 105 a driving shaft, a driven shaft, an internal gear fast on the driven shaft, an eccentric fast on the driving shaft, a driving gear loosely mounted on said eccentric and meshing with the internal gear, a plate fast to the driving gear, a second eccentric fast on the driving shaft, springs mounted on said plate, a casing fast on said second eccentric, 110 arms pivotally connected at one end to said casing, and sleeves adjacent said springs to which the other ends of said arms are pivotally connected, whereby yieldingly restrained independent movement is permitted 115 between the driving gear and the driven shaft.

In testimony whereof I have signed this specification.

JOHN R. ROGERS.
